UNITED STATES PATENT OFFICE.

WILLIAM W. TAYLOR, OF SOUTH DARTMOUTH, MASSACHUSETTS.

IMPROVED TREE-PROTECTOR.

Specification forming part of Letters Patent No. 29,730, dated August 21, 1860.

To all whom it may concern:

Be it known that I, WM. W. TAYLOR, of South Dartmouth, in the county of Bristol and State of Massachusetts, have invented a new and useful improvement in the construction of tree-protectors designed to entrap and destroy noxious insects, such as creep up and down the body of the tree; and I hereby declare the following to be a full and exact description thereof, reference being had to the accompanying drawings and references thereof.

The invention consists, first, in the manner of making the trough in two or more parts and put together as hereinafter shown; second, in the use of a cloth or other equivalent screen as a substitute for packing between the trough and the tree; third, in the method of using the roof or dome cover B of the trough.

In the accompanying drawings, Figure 1 represents the form of the trough A for holding the liquid used to entrap the insects, cast or otherwise made in two pieces. Fig. 2 shows the dome, generally made of tin-plate, and capable of being set as an inverted cone when required. Fig. 3 is a semi-sectional view, showing the tree, the trough, the dome, and the cloth screen in place. The same is shown in Figs. 4 and 5. Fig. 4 shows the adaptation of the inverted dome to inclined trees. Fig. 6 represents a section of the protector with the cloth attached to flange W.

In the drawings, A represents the trough, of cast metal.

B represents the dome or cover, generally of sheet metal.

C represents the tree.

D represents the cloth screen, arranged between the trough and tree.

d represents an iron or metal ring, to which the cloth is fastened by pinching the metal against it or by sewing it to the metal.

d' represents a belt fastened around the lower part of the cloth, fastening it to the tree.

The roof or cover B of my protector is made with the concavity of the dome on the under side when the trees are erect; but when the tree is inclined or crooked, with short bends, &c., then I invert the cover so as to have the concavity above instead of beneath. The object of this inverting of the cover so as to present the concave part above is chiefly to ob-

viate the expense of making a larger cover, otherwise required to prevent the fall of rain and leaves of trees and the sun's rays from entering the troughs and deteriorating the liquid by evaporation on the one hand and diluting it on the other, or by filling up the troughs so that insects can creep across, for it must be observed that in the case of inclined trees the trough and the dome must each be horizontal, and in so arranging them the vertical axis of the dome will not coincide with the axis of the trough, but will fall considerably without it. The remedy most available in this case has been found in inverting the cover and turning the rain and water upon the body of the tree, and which finds its way down between the body of the tree and the trough, as shown in the drawings, Figs. 4 and 5. This whole device, as shown in Fig. 5, where the cloth screen extends down from the inner edge of the circular trough, presents an additional point of utility. The cloth screen has been called a "substitute" for the packing generally used between the tree and the trough, which becomes a nidus for the breeding of insects, and is in that case often pulled out by birds feeding on such insects. The cloth screen obviates such evils, and besides answers an additional purpose—namely, it (the cloth) forms a kind of screen for the insects to travel over, and at the same time constitutes an inverted conical bag capable of being filled with common salt, which is gradually dissolved by the rains and damp weather, and gradually trickles down the body of the tree, and thus prevents the action of a very noxious insect called the "borer," that injures very much young apple-trees, peach, quince, and several other trees. Common salt is exceedingly poisonous to these animals, and this mode of using it presents to the present apparatus great advantages not hitherto found in any other of this class of apparatus.

The salt is usually mixed up with sawdust or some other diluting material in about equal measures, and the space between the cloth and the tree is filled with the mixture. The cloth is sometimes attached to a downward-projecting flange, w, as seen in Fig. 6.

The trough is generally constructed of cast-iron, as represented in the drawings, in two

pieces, put together with flange-joints, screw-bolts, and a gasket of rubber or paper, or even common putty, while it is around the tree. These troughs have been made by striking them up from sheet metal, as zinc, copper, tin-plate, &c.; but from present experience cast is better than wrought metal, and iron preferable to other metals.

The inner flange of the trough is made to receive a metal hoop usually turned over its top or resting on its top in any suitable manner, and to which hoop the cloth screen or bag is closely attached at its upper end, while the lower end passes down between the trough and the tree in the form of an inverted cone, and is tied closely to the tree at its lower end, so that insects climbing the tree shall pass over the cloth screen and the outer flange of the trough and through or over the liquid in the trough in order to get up the tree.

The trough is usually fastened to the tree by means of metal strips soldered or wires fastened to the inner flange, and the opposite ends nailed to the tree or fastened in any other equivalent way.

The roof or dome is made conical or concavo-convex, with the idea of shedding rain, so large as merely to carry the drip outside of the trough. This arrangement of the dome answers perfectly well for all cases where the tree is erect; but when the body of the tree is inclined, either generally or in short bends, the trough being necessarily horizontal, I find it much more economical to invert the dome and turn all the drip toward the tree. This arrangement and the object of it having been already described require no further explanation here. There are mistakes sometimes made by the workman in setting the trough too near the edge of the dome, so that the insects may be supposed to pass directly from the outer flange or edge of the trough to the outer edge of the dome, and thence directly up the tree, without passing through the liquid in the trough; and this is true when the trough and the dome are of

the same metal; but when the trough is made of one metal and the dome of another the animal cannot or will not pass from the trough directly to the dome, from the fact that the animal while one part of his body touches the metal of the trough and the other touches the metal of the dome a galvanic circuit is formed between the two metals and the animal, which is galvanized the instant he touches the metal of the dome. The shock causes him to fall back on the outer edge of the trough, and any subsequent effort of the animal in the same way is attended with the same result. Under these circumstances the supposed danger in placing the dome and trough too near each other is only real when the two are made of the same metal. It is also a condition of the galvanic current being formed that the trough and the dome shall have in some part of their substance a metallic contact, the moisture of the animal having the same effect as an intervening liquid usually required in galvanic circuits of various kinds.

Having now fully described the nature of the invention and the method of carrying the same into full operation, what I claim as my invention, and desire to secure by Letters Patent, is—

1. Making the tree-protecting trough in two parts, prepared and put together substantially as set forth in the specification.

2. The use of the cloth screen or its equivalent for the purpose of guiding the insects climbing over the trough in place of the packing now used, and as a receptacle for salt or its equivalent, all in the manner and for the purposes set forth.

3. Arranging the dome of a tree-protector so as to throw the drip toward the tree and between the trough and the tree, substantially as set forth.

WM. W. TAYLOR.
